(57) **CLAIM**

The ornamental design for an electronic lock device, as shown and described.

DESCRIPTION

FIG. 1 is a front, right, and top perspective view of a first part of an electronic lock device, showing my design.

FIG. 2 is a front elevation view of the first part of the electronic lock device.

FIG. 3 is a rear elevation view of the first part of the electronic lock device.

FIG. 4 is a left side elevation view of the first part of the electronic lock device.

FIG. 5 is a right side elevation view of the first part of the electronic lock device.

FIG. 6 is a top plan view of the first part of the electronic lock device.

FIG. 7 is a bottom plan view of the first part of the electronic lock device.

FIG. 8 is a front, right, and top perspective view of a second part of the electronic lock device, showing my design.

FIG. 9 is a front elevation view of the second part of the electronic lock device.

FIG. 10 is a rear elevation view of the second part of the electronic lock device.

FIG. 11 is a left side elevation view of the second part of the electronic lock device.

FIG. 12 is a right side elevation view of the second part of the electronic lock device.

FIG. 13 is a top plan view of the second part of the electronic lock device.

FIG. 14 is a bottom plan view of the second part of the electronic lock device.

FIG. 15 is a front, right, and top perspective view of the electronic lock device comprising the first part and the second part.

FIG. 16 is a front elevation view of the electronic lock device comprising the first part and the second part; and, FIG. 17 is a reference view of the electronic lock device showing a status when the electronic lock device is mounted on a door.

The broken lines shown in the drawings are included for the purpose of illustrating environment and form no part of the claimed design.
